UNITED STATES PATENT OFFICE.

WILLIAM K. McAFFEE, OF EDGEWOOD PARK, PENNSYLVANIA, ASSIGNOR TO WESTINGHOUSE ELECTRIC & MANUFACTURING COMPANY, A CORPORATION OF PENNSYLVANIA.

COIL SUPPORT FOR DYNAMO-ELECTRIC MACHINES.

1,427,401.

Specification of Letters Patent. Patented Aug. 29, 1922.

Application filed October 13, 1917. Serial No. 196,383.

To all whom it may concern:

Be it known that I, WILLIAM K. McAFFEE, a citizen of the United States, and a resident of Edgewood Park, in the county of Allegheny and State of Pennsylvania, have invented a new and useful Improvement in Coil Supports for Dynamo-Electric Machines, of which the following is a specification.

10 My invention relates to dynamo-electric machines and particularly to supports for the field-magnet coils thereof, and it has for its object to provide a coil support which shall be simple and inexpensive to manufacture and strong and durable in service and which shall hold the coil firmly in position and require a minimum amount of space in which to be assembled.

Heretofore, the field-magnet coils of dynamo-electric machines have been held in position by coil supports in which the coil-supporting portions were integral with the base portions. These structures have been found serviceable under ordinary conditions but cannot readily be used where the space is limited, as, for instance, where it is desired to assemble another winding on the same core between said core and said first winding.

30 According to my invention, I provide a coil support in which the base and coil-supporting portions are separate and which may be assembled in a space which is so limited that it would be impossible to use the one-piece type of support.

Referring to the accompanying drawings, Fig. 1 is a fragmentary elevational view of a dynamo-electric machine, embodying a coil support constructed in accordance with my invention. Fig. 2 is a sectional view of the structure shown in Fig. 1, taken along the lines II—II thereof. Fig. 3 is a detail view of the coil support shown in the other figures.

45 Referring more particularly to the drawings, a machine frame 1 is shown which carries a plurality of field-magnet pole-pieces 2, only one of which is shown. The pole-piece 2 preferably comprises a number 50 of punchings which are held together between end members 3. A field-magnet coil 4 surrounds the pole-piece 2, and a compensating winding 5 is inserted in slots in the end thereof. Connecting leads 6 between 55 the compensating windings of the various

poles extend upwardly between the coils 4 and the pole-pieces 2. The coil 4 is supported, at one side, by a supporting member 7, comprising a one-piece base member and supporting portion but, on the opposite side of the pole-piece 2, on account of the space between the leads 6 and the coil 4 being very limited, it is impossible to insert a support of the type shown at 7. A two-piece support 8 comprises a base member 8^a and a supporting member 9 which is a single piece of metal so bent as to have oppositely extending right angle projections 10 and 11 at its ends. The projection 10 is longer than the projection 11, and engages the coil. The projection 11 fits over the base 8^a, and is attached thereto by means of bolts 12, which extend through the supporting member 9 and the base member 8^a, into the end member 3 of the coil.

75 When the coil 4 is being assembled, it is first moved so that one side of it engages one set of the leads 6, thus permitting the insertion of a support of the one-piece type, shown at 7, between the opposite side of the coil and the opposite set of leads 6. The coil 4 is then moved into its final position. This allows very little space for inserting a coil support on the other side of the coil, so that a one-piece coil support of the type 80 shown at 7 cannot be used since it could not be inserted between the coil and the compensating winding leads. Therefore, a two-piece support of the type described in my present application is used, since it requires 85 very little space in which to be assembled.

90 While I have shown one form of my invention, and described in detail one application of the same, it will be obvious to those skilled in the art that it is not so 95 limited but is susceptible of various minor changes and modifications without departing from the spirit thereof, and I desire, therefore, that only such limitations shall be placed thereupon as are imposed by the 100 prior art or are specifically set forth in the appended claims.

I claim as my invention:

1. In a dynamo-electric machine, the combination with a core member provided with a coil, of a plurality of coil supporting members for said coil, one of said supporting members being formed in two parts and comprises a base portion attached to one side of said core member and a portion disposed inter- 110

- mediate said coil and said core member and adapted to engage said coil at one end and to be fastened to said base portion at the other end.
5. 2. In a dynamo-electric machine, the combination with a core member provided with a coil, of a plurality of supporting members for said coil one of said supporting members being formed in two parts and comprising a 10 base portion attached to one side of said core member and a portion disposed intermediate said coil and core member and having a right-angle projection at one end to engage the coil and a projection at the other end 15 which is adapted to be fastened to said base portion.
3. In a dynamo-electric machine, the combination with a core member provided with a coil, of a plurality of supporting members 20 for said coil, one of said supporting members being formed in two parts and comprising a base portion attached to one side of said core member and a portion disposed intermediate said coil and said core member 25 having a right-angle projection at each end thereof, one of said projections being adapted to hold said coil in position, and the other being adapted to fit over, and be attached to, said base portion.
30. 4. In a dynamo-electric machine, the combination with a core member provided with a coil, of a supporting member for said coil comprising a base portion attached to said core member and a portion having a 35 right-angle projection at each end thereof, one of said projections being relatively long and adapted to hold said coil in position and the other being relatively short and extending in the opposite direction from said long 40 projection to fit over, and be fastened to, said base portion.
5. In a dynamo-electric machine, the combination with a core member provided with a coil, of a supporting member for said coil 45 comprising a base portion attached to said core member and a portion having a right-
- angle projection at each end, one being relatively long adapted to hold said coil in position and the other being relatively short to facilitate assembling and extending in the 50 opposite direction from said long projection to fit over, and be bolted to, said base portion.
6. In a dynamo-electric machine, the combination with a core member provided with a coil, of a supporting member for said coil comprising a base portion bolted to said core member and a portion so bent as to have a right-angle projection at each end thereof, one of said projections being relatively long 55 and adapted to hold said coil in position and the other being relatively short to facilitate assembling and extending in the opposite direction from said long projection to fit over 60 said base portion, and bolts fastening said supporting portion to said base and said base to said core member.
7. In a dynamo-electric machine, the combination of a core member provided with a coil, and a plurality of supporting members 70 for said coil, one of said supporting members being formed in two parts and comprising a coil-engaging portion and a base portion therefor adapted to be inserted between said core and said coil and connected 75 together and to said core and coil members subsequently to the positioning of said coil about said core.
8. In a dynamo-electric machine, the combination of a core member having a coil, 80 and a plurality of coil supporting members one of which is formed in two parts and comprises a coil-engaging portion and a core-engaging base portion adapted to be inserted between said core and said coil and 85 operatively connected together and to said core and coil members subsequently to positioning said coil about said core.
- In testimony whereof, I have hereunto subscribed my name this 5th day of Oct., 90 1917.

WILLIAM K. McAfee.
